UNITED STATES PATENT OFFICE.

MARSHMAN W. HAZEN AND OTTO PETERMANN, OF NEW YORK, N. Y., ASSIGNEES, BY
MESNE ASSIGNMENTS, TO CORONA TYPEWRITER COMPANY, INCORPORATED, A COR-
PORATION OF NEW YORK.

PLATEN-SHIFT.

1,178,446.

Specification of Letters Patent.

Patented Apr. 4, 1916.

Original application filed March 27, 1909, Serial No. 486,181. Divided and this application filed June 7, 1909, Serial No. 500,697. Renewed August 31, 1915. Serial No. 48,350.

To all whom it may concern:

Be it known that we, MARSHMAN W. HAZEN and OTTO PETERMANN, citizens of the United States and of the Republic of Switzerland, respectively, and residents of New York, county and State of New York, have invented certain new and useful Improvements in Platen-Shifts, of which the following is a full, clear, and exact description.

10 This invention relates more particularly to platen shifts for typewriting machines, and is a division of our pending application, Sr. No. 486,181, filed March 27th, 1909, which has matured into Patent No. 1,094,560, dated Apr. 28, 1914.

15 The primary object of the invention is to provide simple and efficient means whereby a carriage may have two frame members, in one of which the platen is mounted, and 20 which is adapted to have a relative movement with respect to the other frame member so as to permit the same to be properly shifted to adapt the type-bars to have a plurality of characters thereon.

25 A further object of the invention is to provide simple means for moving the platen vertically and at the same time permit the platen and its support or frame member to form a part of the carriage.

30 With these and other objects in view, the invention will be hereinafter more particularly described with reference to the accompanying drawings, which form a part of this specification, and will then be pointed 35 out in the claims at the end of the description.

35 In the drawings, Figure 1 is a rear elevation of one form of machine embodying our invention. Fig. 2 is a longitudinally sectional view. Fig. 3 is a detail view of one of the carriage frame members detached. Fig. 4 shows how one of the carriage frame members is slotted to permit relative movement of the other frame member; and Fig. 5 is a fragmentary side elevation of the carriage and frame, showing a part of the guiding means for the vertically, movable frame member.

40 The machine has a frame 10 of any suitable construction, and supported within the frame are brackets 11 in which a plurality of key-levers 12 are pivoted, and these levers each have a pin 13 which engages a slot 14 in the end of a type-bar 15. The type-bars

when moved to printing position engage the 55 surface of a platen 16 which is supported on a carriage 17.

Instead of the type striking against the usual cylindrical platen, the type may engage a flat surface, as 18, formed as a part 60 of the plate-like platen 16 which extends transversely of the machine and is movable with the carriage 17, the said carriage having two frame members 19 and 20 to the former of which the plate 16 is secured. The 65 plate 16 may be curved for a greater part of its width except at the straight part 18, forming the printing point, and said platen may be secured to the part 21 of the carriage frame member 19 or otherwise held as desired in a position so that the paper or work 70 may be readily passed about the same, though instead of the type striking directly against a metal surface, a yielding surface or strip 21^a may be provided and said strip 75 may be so attached that it may be readily replaced in case of wear. A bar 22, Figs. 1 and 2, extends transversely of the machine to the rear of the fixed platen 16, and to the bar may be held the work-engaging fingers 80 22^a which may be adjustable along the bar 22 by means of the screws 22^b. By this means the work may be properly guided about the platen 16 so as not to interfere 85 with the type and cause the same to make two impressions where a plurality of characters are formed on the type head, as the work immediately on leaving the printing point is made to bend over the surface of the curved platen.

90 A roll 23 corresponding to the usual platen roll may be journaled in the frame member 19 of the carriage 17, and may be provided with finger pieces or handles 24 by which the roll may be rotated, the said finger 95 pieces 24 being secured to the shaft of the roll 23, and to permit the roll and platen frame to move vertically the carriage frame member 20 is slotted at 24^a where the shaft passes through said member. At the rear 100 of the roll 23 is a second smaller roll 25, which normally engages the roll 23, and at the front of said roll 23 is a still smaller roll 26. The shaft 27 of the roll 25 is held in slots 28 in the frame member 19 and has peripheral grooves at the ends thereof, and held to the ends of the shaft in such a way as to permit the shaft to rotate are the 105

2

springs 29 which have one end connected to levers 30. These levers 30, Fig. 3, are pivoted at 31, and have their outer ends, as 32, adapted to be engaged by screws 33, so that the tension of the springs 29 may be varied and the roll 25 yieldingly held against the larger roll 23. The roll 26 is similarly held to the roll 25 and has the ends of its shaft 34 held to slide and rotate in the slots 35 of the carriage frame member 19, and connected to said shaft are the springs 36 which are connected to the levers 37, the latter being pivoted at 38 and normally forced in one direction by screws 39 to vary the tension of said springs.

The platen may be raised or lowered to different degrees according to the number of characters or type on the type-bars 15. If there are three characters there should be two shift keys and if only two characters only one shift key is necessary. In the form shown only one shift key is provided for the purpose of illustrating how the platen may be raised. The shift key-lever 40 is held to a transversely-extending rod or shaft 41, and its inner end is pivotally connected at 42 to the vertically-extending bars 43, the latter being connected to move in unison and may be braced by means of the rod 44. One of the bars 43 may be provided with a projection 45 which is limited in its movement by means of the screws 46 arranged at the upper and lower portion of a bracket 47 secured to one of the side members of the frame. The upper end of the bars or members 43 may be secured to a transversely-extending bar 48 which is adapted to move vertically with the platen and its frame member 19, as the platen in this instance moves vertically and not the entire carriage. As before stated only one shift key-lever is shown, but two may be provided which are adapted to move the platen and paper feed mechanism, as 49, and to lock the same in its adjusted position to position the platen for either the upper case letters or figures.

To properly support the carriage and the platen and paper feed, and to compensate for wear, we may provide a ball-bearing connection between the carriage and the machine frame or parts thereof, to adapt the carriage and platen to move readily across the machine. Adjacent to the bar 48 is a normally fixed bar 50 extending transversely of the machine in which may be arranged screws 51 or other devices to serve as guides for the vertically movable bar 48, and extending between the side members of the carriage frame member 20 is a brace bar 52. A bearing bar 53 is arranged directly over the bearing bar 48, and said bearing bar 53 may move vertically between the pins 54 projecting inward from the side members of the carriage frame. The pins serve to guide

the bar 53 in its vertical movement with the platen, and interposed between the bearing bars 52 and 48 are balls or bearing members 55. These bearing members may be two in number, and may be connected by a wire 70 to move in unison, and extending upward from the bar 48 may be one or more brackets 56 the upper end of which may be bent at any angle to extend over the upper surface of the bar 53. The bar 50 is fixed to 75 the machine frame while the bar 52 is fixed to the carriage, and the bearing bars 48 and 53 are both movable vertically with the platen frame member 19 independent of the carriage frame member 20, though only the bar 52 moves transversely with said carriage frame members.

A second bearing 57 is provided. This bearing comprises a plurality of bars or members 58, 59 and 60. The intermediate 85 bar or bearing member 59 is fixed to the main frame, and the upper surface of said bar as well as the lower surface of bar 60 are each provided with a V-shaped groove in which the bearing balls or members 61 are supported, and under the bar 59 are the bearing balls or members 62, the said bars being sufficiently spaced apart to permit the said balls to be properly supported between the same.

The lower bearing bar 48 with the upright bars or members 43 and the transverse rod 44 connecting the lower ends of the bars 43 together form a substantially rectangular and rigid frame whereby the bearing bar 100 48 and the platen may be positively elevated by the platen shift levers from both sides of the machine. The platen will thus be prevented from tilting and the bearing will be rigidly maintained in any of its shifted 105 positions.

It will be understood that instead of the normally stationary platen shown in the drawings, the usual form of platen may be employed.

While we show and describe certain features of the machine other than the platen shift, such features are covered in other co-pending applications. The feed mechanism is claimed in our application Sr. No. 500,698, 115 filed June 7, 1909; the paper feed in our application Sr. No. 500,696, filed June 7, 1909; the platen in our application Sr. No. 500,695, filed June 7, 1909; and the key-levers in our application Sr. No. 500,694, 120 filed June 7, 1909.

From the foregoing it will be seen that simple and efficient means are provided for moving the platen vertically with respect to the other part of the carriage to adapt the 125 same to permit the type-bars to have a plurality of characters thereon; and that a simple and efficient frame for the platen and carriage is provided.

Having thus described our invention, we 130

claim as new and desire to secure by Letters Patent:—

1. In a typewriting machine, the combination with printing mechanism, of a support, a carriage having two frame members adapted to move along said support, a platen mounted in one of the frame members, a bar extending transversely of the support and fixed thereto, a vertically-movable bar slidingly held in the support and arranged in parallel relation with the first-mentioned bar, screws projecting from the first-mentioned bar and serving to guide the vertically-movable bar, a bar carried by the carriage frame member on which the platen is mounted and located above the vertically-movable bar, a ball-bearing connection between said bars, means for elevating said latter bars and platen and also the frame in which the platen is mounted, and a ball-bearing connection for the other carriage frame member.
2. In a typewriting machine, the combination with printing mechanism, of a support, a carriage having two frame members adapted to move along said support, one of which is vertically slidable within the other, a platen mounted in one of the frame members, a bar extending transversely of the support and fixed thereto, a vertically-movable bar slidingly held in the support and arranged in parallel relation with the first-mentioned bar, a bar carried by the carriage frame member on which the platen is mounted and located above the vertically-movable bar and connected to cooperate therewith, and means for elevating said bars and platen and also the frame in which the platen is mounted.
3. In a typewriting machine, the combination with printing mechanism, of a support, a carriage adapted to move along said support, a platen mounted in the carriage, a

guide bar extending transversely of the support and fixed thereto, a vertically movable bearing bar slidingly held in the frame and arranged in parallel relation with the first-mentioned bar, a second vertically movable bearing bar carried by the carriage and located adjacent to the slidingly held bar and coöperating therewith, and means for elevating said bars and platen.

4. In a typewriting machine, the combination of a carriage having a bearing, a platen mounted upon the carriage, an independent bearing including transversely-extending bars having relative lengthwise movement but also adapted to move vertically with the platen, upright bars or members connected to the lower bearing bar and rigidly held thereto, means for limiting the upward movement of said bars, a transversely-extending rod connecting the upright bars at the lower end to provide a substantially rigid frame, and a shift lever connected to the frame and adapted to elevate the same.

5. In a typewriting machine, the combination of a carriage having a bearing, a platen mounted upon the carriage, and independent bearing including transversely-extending bars having relative lengthwise movement but also adapted to move vertically with the platen, upright bars or members connected to the lower bearing bar and rigidly held thereto, means for limiting the upward movement of said bars, and a shift lever connected to the frame and adapted to elevate the same.

This specification signed and witnessed 80 this 4th day of June, A. D. 1909.
